MAGNETIC PUZZLE

Thomas H. Darling and William Maccabee,
Rockville Centre, N. Y.

Application March 24, 1933, Serial No. 662,514

4 Claims. (Cl. 273—157)

This invention relates to what are commonly known as puzzles, referred to as jig saw puzzles, employing a plurality of puzzle parts or elements of numerous shapes, designs or contours adapted to be assembled in a proper relationship with respect to each other in the completion of the puzzle and production of a predetermined picture, design or representation; and the object of the invention is to provide a puzzle of the class described wherein the puzzle pieces or elements are either composed wholly of magnetically influenced material or partially of such material to permit their placement and arrangement on a magnetized plate to facilitate the supporting of the puzzle elements on the plate against displacement with respect to each other in the process of solving the puzzle and completing the picture representation thereof; a further object being to provide in conjunction with the puzzle elements a magnetized plate or table and a tool by means of which puzzle pieces may be removed from and applied to the magnetized plate or table in the operation of assembling the puzzle elements, said tool involving a suction cup for lifting and transporting the puzzle elements and means for releasing the elements from the suction cup; and with these and other objects in view, the invention consists in an amusement device of the class and for the purpose specified which is simple in construction, efficient in use and which is constructed as hereinafter described and claimed.

The invention is fully disclosed in the following specification, of which the accompanying drawing forms a part, in which the separate parts of our improvement are designated by suitable reference characters in each of the views and in which:

Fig. 1 is a plan view of a magnetic plate or table showing a number of puzzle or game pieces arranged thereon.

Fig. 2 is a partial section of the structure shown in Fig. 1 on an enlarged scale, and showing a tool which we employ.

Figs. 3, 4 and 5 are sectional views of several forms of puzzle or game pieces that we may employ.

Fig. 6 is a perspective view of another form of puzzle or game piece; and,

Fig. 7 is a sectional view of a part of a table or supporting plate showing a slight modification.

In carrying the invention into effect, a number of puzzle or game pieces 10, preferably of different contours, are adapted to be assembled on a plate or table 11 in a predetermined relation-

ship with respect to each other with the separate pieces interlocking and intermeshing with each other to produce a complete picture or representation as in other puzzles of the class under consideration.

The plate or table 11 is magnetized and the game pieces 10 include magnetic metal or material so that in placing the puzzle or game pieces upon the plate 11, the same will be retained in position thereon against accidental displacement. The game pieces shown in Figs. 1 and 2 are composed of a magnetic metal and are characterized by printing, painting, lithographing or the like on one or both side faces thereof to represent a predetermined picture or pictures when the game pieces are assembled. It will thus be seen that by virtue of the material employed in the game pieces 10 and the fact that the plate 11 is magnetized, the pieces 10 will maintain a position in which they are placed on the plate without danger of accidental displacement and in this way, the solution of the puzzle is materially simplified as well as in creating added interest to both young and old in the solution of the puzzle. Furthermore, it will be apparent that the plate 11 may be characterized to form a framing or like supporting body so that after the several pieces of the puzzle have been applied thereto, the same may be hung up on a wall in the manner of hanging pictures and the like.

In Fig. 4 of the drawing, we have indicated at 12 a modified form of puzzle or game piece which consists in providing a magnetic surface 12a thereon and a non-magnetic surface 12b, the portions 12a and 12b being secured together in any suitable manner, and the surface 12a may be composed of a sheet of magnetic metal whereas the surface 12b may be composed of paper, cardboard, wood, fibre, rubber or any other similar material.

In Fig. 5 of the drawing, we have shown at 13 another form of puzzle or game piece which includes two outer, non-magnetic surfaces 13a and 13b and an intermediate filler 13c of magnetic material which may be a strip or sheet of material or a metallic composition including a binder adhering the filler 13c to the outer surfaces 13a and 13b. In this connection, it will be understood that the filler 13c may be composed of a powdered granular metallic material or metallic filings, and these metallic particles may be included in a sizing, paint or other binder which supports them together and to the facings as described.

In Fig. 6 of the drawing, we have shown at 14

another form of puzzle or game piece which is substantially similar to that shown in Fig. 4, the primary difference being that the metallic facing 14a on one side of the non-metallic or non-magnetic facing 14b is composed of granular magnetic particles secured to the surface of the facing 14b, and as before stated, these metallic particles or elements may include a suitable binder or sizing which will support the same upon the facing 14b or may be in the form of a metallic paint.

At this time, it will be understood that various other forms and constructions of the puzzle or game pieces may be employed, the essential feature being the provision in or on such pieces of magnetically influenced material in sufficient volume to prevent accidental displacement of said pieces when placed upon or disposed over and in close proximity to the plate 11. In this connection, it will be understood that the puzzle or game pieces do not necessarily have to be placed directly upon the magnetic plate. For example, we have shown in Fig. 7 of the drawing the magnetic plate or table 11a on the upper surface of 25 which is a sheet or covering 11b of non-magnetic material such for example as glass, fabric, paper and the like upon which the puzzle or game pieces may be placed and retained in position by the influence of the magnetism of the plate 11a. It will also be apparent that any means may be provided for retaining the magnetism of the plate or in renewing the same.

In Fig. 2 of the drawing, we have shown at 15 a hand tool by means of which the puzzle or game pieces may be conveniently raised from the plate or table 11, 11a, placed in a desired position thereon in the solution of the puzzle and then released from the tool. This tool consists of a rubber suction cup 16 at the lower end thereof 40 which will have sufficient suction to release the game pieces from the table against the magnetic influence of the table, and a plunger 17 having a non-magnetic end 18 disposed within the suction cup to forcibly remove the puzzle pieces from the cup when in proper position.

The cup 16 is disposed at one end of a tubular casing 19 in which the plunger is slidably mounted. The plunger 17 projects through the upper end of the casing 19 and has a finger piece 17a by means of which the plunger may be depressed, as will be understood. The plunger rod 17 fits tightly in the aperture of the cup 16 through which it passes so as to be frictionally held in raised position and is forcibly depressed against this friction in releasing a game piece. It will also be understood that the plunger is raised in the operation of depressing the suction cup 16 on one of the game pieces. In the use of the device, the casing 19 will be grasped by one hand and the suction cup 16 thereof forced down 55 upon a puzzle piece, thus attaching the same to the cup 16 permitting the same to be lifted from one point of the table or any other support and the placement thereof on the table in a desired position in the solution of the puzzle, and when so placed, one finger of the hand will be used to depress the plunger 17 to disengage the puzzle piece from the cup. It will be understood that the cup 16 will be sufficiently simple to engage the smallest puzzle pieces, but it will also

be apparent that the use of the tool is not absolutely essential as the puzzle pieces may be handled by hand. However, the said tool will eliminate the magnetic influence of the plate in the operation of placing the puzzle pieces in proper position.

It will be understood that the entire puzzle or game may be constructed in miniature or large sizes, and in the construction of miniature devices, the puzzle or game pieces including the 10 magnetic plate and tool may be packed in a suitable container, and for this purpose, the magnetized plate may consist of two or more pieces. It will be understood that various other changes in and modifications of the construction herein shown and described may be made within the scope of the appended claims without departing from the spirit of our invention or sacrificing its advantages.

Having fully described our invention, what we 20 claim as new and desire to secure by Letters Patent, is:

1. A puzzle device of the class described comprising a magnetized supporting member, said member being magnetized throughout the entire surface thereof, a plurality of interfitting game pieces adapted to be arranged on any exposed surface of said member in edge to edge relation with respect to each other, and said game pieces including means establishing a magnetic attraction to said member whereby said game pieces when placed on said member will be maintained against accidental displacement therefrom.

2. A puzzle device of the class described comprising a magnetized supporting member, said member being magnetized throughout the entire surface thereof, a plurality of interfitting game pieces adapted to be arranged on any exposed surface of said member in edge to edge relation with respect to each other, said game pieces including means establishing a magnetic attraction to said member whereby said game pieces when placed on said member will be maintained against accidental displacement therefrom, and said game pieces having facings of non-magnetic material.

3. A puzzle device of the class described comprising a magnetized supporting member, said member being magnetized throughout the entire surface thereof, a plurality of interfitting game pieces adapted to be arranged on any exposed surface of said member in edge to edge relation with respect to each other, said game pieces including means establishing a magnetic attraction to said member whereby said game pieces when placed on said member will be maintained against accidental displacement therefrom, and said member including a thin surface of non-magnetic material.

4. In a puzzle device employing a game plate magnetized throughout the entire area thereof, a plurality of interfitting game pieces of irregular contour adapted to be assembled and retained on said plate in the production of a predetermined picture, each of said pieces comprising magnetically influenced material, and a facing of non-magnetic material.
